UNITED STATES PATENT OFFICE

2,465,372

TELEPHONE SYSTEM

Bernard C. Groh, Orange, N. J.

Application August 10, 1945, Serial No. 610,165

2 Claims. (Cl. 315—129)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention relates to telephone systems.

Telephone systems commonly employ a switchboard signalling device whereby the switchboard operator may be made aware that a signal has been impressed on a given line. In an ideal system, the signal device would be responsive to signals of a predetermined character and would be nonresponsive to other signals. Heretofore this desired performance has not been obtained, since momentary surges of electrical energy from sources external to the telephone circuit have been able to cause the switchboard signal device to operate, thus impressing a false indication of an incoming signal on the system.

It is therefore an object of the invention to provide a telephone system of a novel character whereby switchboard signal devices may be triggered only when a signal of a predetermined character is impressed on the line.

In a preferred embodiment of the invention, means are positioned in the electrical circuit between the source of signal energy and the signal responsive switchboard device whereby the signal responsive device will be triggered only by signals of a predetermined character, the said means comprising a discriminator circuit of a novel character.

A better understanding of the invention will be obtained from the following description of the preferred embodiment of the invention, read in connection with the accompanying drawing, in which the figure is a schematic circuit diagram of the said preferred embodiment.

Referring to the figure, a discriminator circuit 10, comprising non-inductive resistance arms 12 and trigger arm 14, is electrically positioned between a signal generator 16 such as a field telephone, and a four element neon signal device 18.

The discriminator circuit 10 is in the form of a Wheatstone bridge. The trigger arm 14 comprises a thermistor. Thermistors are well known in the art and are characterized by negative resistance characteristic. More specifically, the resistance of a thermistor decreases after a current has passed therethrough for an appreciable amount of time. This negative resistance characteristic is caused by the thermal effect of the current passing therethrough. It is therefore a result, that if a very short surge of current passes through the element there will be no appreciable resistance change, whereas if a current having a

2

duration sufficient to heat the element passes therethrough, the heating caused thereby will be sufficient to cause the resistance of the said element to drop sharply. For example, a current having a duration of $\frac{1}{20}$ of a second will cause the resistance of a standard thermistor to drop from 50,000 ohms to approximately 1500 ohms. This characteristic of a thermistor is utilized in this invention to discriminate against momentary surges of current in a telephone line that heretofore have been sufficient to operate a switchboard signal device and impress thereon a false indication of an incoming signal.

The field telephone 16 provides a signal having a duration sufficiently long to operate the thermistor. This signal transmitted over a transmission line 20, is impressed upon the bridge 10 at conjugate points a , a^1 . The bridge, being normally balanced, does not initially present a potential at points b , b^1 , across which points the neon signal device 18 is connected. However, after the signal current has been impressed upon the bridge circuit 10 for a fraction of a second, the resistance of the thermistor 14 drops sharply, causing a potential to appear across conjugate points b , b^1 , which potential, being impressed upon the elements 22 of neon signal tube 18, is sufficient to trigger the tube.

Assume, however, that a momentary surge of electrical energy occurs in the transmission line 20 somewhere between the discriminator circuit 10 and the field telephone 16. This surge would be impressed upon points a , a^1 of the discriminator circuit 10. However, since the duration of a surge is very short, the heating effect of the surge would not be sufficient to cause the resistance of the thermistor 14 to drop. There would thus be developed no potential across point b , b^1 , and therefore no signal would be indicated on signal device 18.

I have thus provided a means whereby a switchboard signal device may be insulated against momentary surges of energy in a telephone system, the said means being adapted to respond to desired signals.

Although the operation of the invention has been illustrated by a device incorporating a thermistor, it is obvious that any element having a delayed response, whereby the bridge may be unbalanced by an impressed signal, may be substituted for the thermistor.

The neon signal device 18 is provided with a separate pair of electrodes 24 whereby the signal device will remain operative until extinguished by the switchboard operator. The electrodes 24

are connected to battery 26 through key 28. The potential of battery 26 is chosen at a value below the firing voltage of tube 18 but above the extinction voltage thereof. This sustaining circuit is normally closed through key 28, the voltage developed therein being insufficient to fire the tube 18 but sufficient to sustain the tube once it has been fired. Thus if the tube of the device is fired by an incoming signal of a predetermined character operating through discriminator circuit 10, the said tube will remain fired until the key 28 is opened by the switchboard operator. This feature is very important in that it maintains the flash on the board until removed by the operator, thus eliminating the possibility of an incoming signal being overlooked.

It is obvious that many modifications and changes may be made within the scope of the invention, the invention being fully defined in the attached claims.

What is claimed is:

1. The combination, in a telephone system, of signal generating means for signalling an attendant, said signals having a duration in excess of a predetermined value, a bridge network having a pair of conjugate points connected across said source, a resistive element having a predetermined negative characteristic integral in only one of the arms of said network whereby the said network will be rendered unbalanced upon receipt of a signal of the aforementioned characteristic, and means connected across the other pair of conjugate points of said network responsive to and triggerable by the said unbalance, the said responsive means comprising a four element neon lamp, said elements comprising two pairs of electrodes, one pair of said electrodes being connected to the second named pair of conjugate points and the other pair of said electrodes being con-

nected to a source of voltage having a value below the firing point of said lamp and above the extinction value thereof.

2. In a telephone system, the combination of 5 signal generating means for signalling an attendant, said signals having a duration in excess of a predetermined value, a bridge network comprising three arms of resistance elements having a linear resistance characteristic, and a fourth 10 arm including a thermistor, one pair of conjugate points of said bridge network being connected across said generating means, a four element neon lamp, two of said elements being connected to the other pair of conjugate points of said bridge network and being triggered by the 15 unbalance voltage of said bridge upon receipt of a signal of the aforementioned characteristic, the other set of said elements being connected to a source of voltage having a value below the firing point of said lamp and above the extinction value thereof, whereby the said lamp, upon being triggered, will continue to glow upon cessation of 20 said signal until the connection to said source of voltage is broken.
